SAFETY MASTER LOCK

Oliver C. Kemp, Little Rock, Ark.

Application January 9, 1941, Serial No. 373,841

3 Claims. (Cl. 292—33)

This invention relates to a safety master lock for mobile bodies usually having multiple doors, and for example automobiles, aeroplanes and the like.

It is particularly aimed to provide a construction additional to the usual or standard locks and latches for the doors, which may be operated from the interior of the body or the exterior of the body to simultaneously lock and unlock all of the doors, a construction which may be under key control from the outside of the body, and a construction which has novel bolt means for the various doors, and mechanism to control the operation thereof.

The more specific objects and advantages will become apparent from a consideration of the description following taken in connection with accompanying drawings illustrating an operative embodiment.

In said drawings:

Figure 1 is a view in horizontal section, taken fragmentarily through an automobile, aeroplane or like vehicle body equipped with my improvements;

Figure 2 is an enlarged vertical sectional view taken on the plane of line 2—2 of Figure 1;

Figure 3 is a detail section taken on the line 3—3 of Figure 2;

Figure 4 is a detail section taken on the line 4—4 of Figure 2;

Figure 5 is an elevation showing the key controlled lock part;

Figure 6 is an enlarged view of the parts of Figure 4;

Figure 7 is a view similar to Figure 6 but showing the notch-closing member in notch-closing position;

Figure 8 is an enlarged detail section partly broken away of the bar and notch-closer;

Figure 9 is a detail section taken on the plane of line 9—9 of Figure 6, and

Figure 10 is a detail section taken on the plane of line 10—10 of Figure 6.

Referring specifically to the drawings wherein like reference characters designate like or similar parts, the invention may be applied to the body or enclosure of any mobile body such as an automobile, aeroplane or any equivalent and which body is generally designated 10. It is shown as equipped with a plurality of doors 11 on each side thereof, which are hinged on vertical axes 12 to uprights or posts 13 of the body 10 located between them and which doors are adapted to swing outwardly as shown. Said doors are to be taken as conventional and to be

equipped with the usual door lock or latch mechanism installed by the manufacturer of the automobile or aeroplane.

For the doors of each side of the vehicle, lock bolts or rods are provided at 14, 15 and 16 with a follower 17 between the bolts 15 and 16. All of such bolts and followers are aligned but unattached to each other. Bolts 14 are longitudinally slidable in guide tubes or barrels 18 mounted in the body 10 forwardly of the front doors 11, and are urged forwardly to unlocked positions by expansive coil springs 19 within the barrels surrounding the bolts and abutting closures 20 at the inner ends of the barrels and lugs 21 extending laterally from the forward ends of the bolts 14 and through elongated slots 22 in such barrels. In the locked position, said bolts 14 extend into sockets or sleeves 23, in the forward edge portions of the front doors 11. Such sockets 23 and sockets or barrels 24 in the rear edge portions of the front doors 11 slidably mount the bolts 15 and the latter are urged to unlocked position through the expansive action of coil springs 25 abutting the tubes or barrels 24 at one end and an abutment 26 on the rod 15 which is adapted to abut the barrels 23 in the unlocked position of such bolts 15.

In the locked position of the bolts 15, they extend, as shown in Figure 1, into a tubular guide or barrel 27 fixed in the post or partition 13. Bolts 15 abut the follower bolts 17 which are slidably mounted by the barrels 27 in order to move the latter into tubular barrels or guides 28 carried by the rear doors 11 at the front thereof and which mount one end of the bolts 16, the other ends being mounted by guides or tubular barrels 29 mounted in the rear ends of the rear doors 11. Such bolts 16 extend into barrels or tubular sockets 30 in the body 10 so as to lock the doors 11 in which they are mounted. Expansive coil springs 31 surround the rods 16 and at one end abut the tubular barrels 29 and at the other end engage abutments 32 on such rods. In the open position of the rear door 11 abutment 32 will engage the barrel 28. Thus in the open or unlocked position of the doors 11, the rods 15 will be completely within the length of the front doors 11 and the rods or bolts 16 will be completely within the length of the rear doors 11 and the follower bolts 17 will be completely within the barrels 27 or posts 13 so that the doors may be freely operated as usual. It should be mentioned that the follower rods 17 have enlarged heads at 33 adapted to abut the barrels 27 to limit forward movement of the follower bolts and that

such bolts also are surrounded by relatively weak coil springs 34 abutting the heads 33 and barrels 27, to urge the follower bolts forwardly. The dashboard or instrument board of the automobile, aeroplane or like body 10 is conventionally shown at 35, and the cowl wall is suggested at 36 and hood part suggested at 37. Brackets 38 are mounted by the body 10 and journal a transverse operating rod 39 in front of and parallel to the dashboard 35. Cranks 40, rigid with the operating rod 39 rise from opposite ends thereof and have elongated slots at 41 through which the lugs 21 extend. A central crank 42 rises rigidly from the operating rod 39 and to the top thereof is pivoted at 43, a manipulating member or bar 44, which extends through an opening 45 provided in the dashboard 35 and in a latch plate 46 fastened thereto. Bar 44 has a notch 47 which engages the plate or keeper 46 to hold the bar 44 retracted and accordingly cause the cranks 40 to maintain the various locking bolts 14, 15, 16 and 17 in rearmost or door locking position, overcoming the action of all associated springs. Bar 44 is held in such latched position by a contractile coil spring 48 engaging the same and engaging a lug 49 fastened to the rod 39. When the bar 44 is raised the various springs at 18, 25 and 31 will move the rods or locking bolts 14, 15, 16 and 17 to unlocked positions thus enabling normal operation of the doors 11.

In order to prevent latching engagement of notch 47 with keeper 46 so that the parts may be unlocked from the outside, a closer member 48' in the form of a metallic strip or bar is pivoted loosely at 49' on the side of bar 44 for fastening in position exposing the notch 47 as in Figures 4, 6 and 8, or in a position closing such notch as in Figure 7. Bar 48' may also be resilient and have a lug at 50' which is selectively engageable with recesses 51' and 52', provided in the side of bar 44 and adapted to hold the closer 48' respectively in the positions of Figures 6 and 7. To prevent accidental detachment of the lug 50' from either recess 51' or 52', an expansive coil spring 53' bears against such member 48', surrounding a stud 54', and abutting a head 55' thereon and a washer or disk 56' loose on the stud. The stud passes through an enlarged opening 57' in the closer member 48', which opening enables the pivotal movement of the closer member. The closer member also is fastened in any suitable manner to the bar 44 as by means of a screw threaded shank 58'.

Knobs 44a and 48a are provided on bars 44 and 48', respectively, to facilitate their operation.

As a result of the construction described, the doors may be locked by the invention, in addition to the usual locking mechanism thereof, either from the inside of the automobile by an occupant with closer 48' positioned as in Figures 4, 6, 8, 9 and 10 or from the outside of the automobile as when parked with closer 48' positioned to close notch 47, as in Figure 7. The master locking parts are normally unlocked and bar 44 is in its forward position. However, when such master locking mechanism is locked

from the inside of the automobile, the bar 44 is pulled to the position of Figures 4, 6 and 8 with notch 47 exposed, and fastened therein by such notch 47 engaging the keeper 46. Such bar 44 has to be in forward position with notch 47 closed by member 48' to enable the doors to be opened. Hence when the automobile is parked, the key is inserted into the keyhole 50 of a pin tumbler lock so as to enable the cylinder 51 of such lock to be turned through the rotation of a handle 52. Cylinder 51 has a rigid crank 53 thereon which engages the adjacent crank 54. Such a crank 54 is provided rigidly at each end of the operating rod 39 and each has a lug at 55 contacting the crank 40 so that through operation of the key, in keyhole 50, will cause crank 53 to operate adjacent crank 54, thus turning operating rod 39 and causing its crank 42 to move the bar 44 inwardly and the notch 47 to engage the keeper 46. Upon the return of the party possessing the key, it will again be inserted into the hole 50 and the parts operated.

Various changes may be resorted to provided they fall within the spirit and scope of the invention.

I claim as my invention:

1. In combination with a body having doors, co-acting bolts and parts on the doors and body to lock each door, means to cause movement of one bolt through movement of another bolt, said bolts being in alignment, means operable to move the bolts to locked positions, means urging the bolts to unlocked positions and within the confines of the doors whereby they will open with the doors, said operating means comprising a bolt and means to actuate the latter, the actuating means having structure to enable fastening to the body from the inside, and a device to render said structure inoperative for the aforesaid purpose, to enable locking and unlocking from the outside of the body.

2. A locking mechanism of the class described having a bar provided with a notch engageable with a keeper to enable locking of the bar from the inside of an automobile or the like, a closer for the notch enabling locking and operation of the structure from the outside, means pivoting said closer to the bar, a lug on the closer, notches on the bar engageable by the lug to hold the closer in different positions, said closer having an enlarged slot, a stud extending from the bar through said slot, and spring means carried by the stud having expansive contact against the outside of the closer.

3. A locking mechanism of the class described having a bar provided with a notch engageable with a keeper to enable locking of the bar from the inside of an automobile or the like, a closer for the notch enabling locking and operation of the structure from the outside, means pivoting said closer to the bar, means urging said closer into contact with the bar, interengaging means between the closer and bar to hold the closer in different positions.

OLIVER C. KEMP.
